UNITED STATES PATENT OFFICE

OTTO J. GROEHN, OF GROSSE POINTE PARK, AND LAWRENCE S. LAMB, OF GROSSE POINTE, MICHIGAN, ASSIGNORS TO HUDSON MOTOR CAR COMPANY, OF DETROIT, MICHIGAN, A CORPORATION OF MICHIGAN

APPARATUS FOR SHAPING SHEET METAL

Original application filed December 28, 1927, Serial No. 243,030. Patent No. 1,708,615, dated April 9, 1929.
Divided and this application filed February 8, 1929. Serial No. 338,466.

This invention relates to apparatus for shaping sheet metal and more particularly to apparatus for offsetting a flange previously formed by bending a body of sheet metal.

5 This application is a division of our co-pending application Serial No. 243,030, filed December 28, 1927, Patent No. 1,708,615, dated April 9, 1929, which discloses a method of shaping sheet metal to produce a quarter 10 window finish molding for an automobile body.

It is the object of the present invention to provide an apparatus which is particularly suitable for use in offsetting a flange in the 15 practice of the method described in our above mentioned co-pending application.

The invention will be more clearly understood from the following description in conjunction with the accompanying drawings; 20 in which,

Fig. 1 is a plan view of the lower half of an apparatus embodying the invention;

Fig. 2 is a side elevational view of the same;

25 Figs. 3 and 4 are sectional views taken upon line 3—3 of Fig. 1, showing the relation of the parts at the beginning and completion of operation respectively;

Figs. 5 and 6 are sectional views taken 30 upon line 5—5 of Fig. 1; and

Fig. 7 is a plan view of the blank as shaped with the apparatus.

Before explaining in detail the present invention, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the several claims hereto appended as considered in view of the prior art and the requirements thereof.

The apparatus of the invention is adapted particularly for shaping a sheet metal blank previously formed with flanges 7a

and 7b. One embodiment of the invention is illustrated by the apparatus shown in the accompanying drawings which comprises a base 10 having spaced projections 11 extending upwardly therefrom. A suitable member 12 is positioned between the projections 11 and secured upon the top surface of the base in any suitable manner, as by screws 14, and serves to support the body of the blank. A plate 15 is provided with an opening 16 to provide clearance for the member 12 and is movably secured to the base by bolts 17 having threaded engagement with the plate 15 and passing through openings 18 in the base. The openings 18 are provided with shoulders 19 adapted to engage the head of the bolts and serve as a stop therefor. The plate 15 normally is held in an extended position by springs 20 supported in recesses 21 in the base and engaging the lower surface of the plate. 55 60 65 70

A ram 22 is arranged for movement toward and from the base, and with this in view is provided with openings 23 for collars 24 adapted to receive for sliding engagement therewith guides 25 fixed in the base. A recess 26 is provided in the lower surface of the ram directly above the member 12 to receive for movement therein a mandrel 27. The mandrel 27 is held upon the ram 22 by bolts 28 threaded to the mandrel and passing through openings 29 provided with shoulders 30 to engage the head of the bolt and serve as a stop therefor. The mandrel normally is held in extended position by springs 31 within recesses 32 and extending to engage the top surface of the mandrel. Bearing blocks 33 are secured to the lower surface of the ram upon opposite sides of the mandrel 27 in any suitable manner, as by screws 34. 75 80 85 90

Dies 35 are movably mounted upon the plate 15 on opposite sides of the member 12 and are provided on their inner surface with wearing blocks 36 secured thereto in any suitable manner, as by screws 37. A wearing block 40 is secured, as by screws 41, to the outer lower edge of each die and each is adapted for engagement with a wearing 95 100

block or cam 42 upon the inner surface of one of the projections 11.

Suitable means are provided for holding the dies away from the mandrel 27 and member 12. For this purpose brackets 45 are secured to the plate 15 in any suitable manner, as by screws 46, and are provided near their upper free ends with openings 47 to permit the free passage of bolts 48 secured at one end to the dies 35. A spring 49 surrounds each bolt 48 and extends between the brackets 45 and washers 50 positioned and held near the free ends of the bolts by nuts 51.

In performing this operation the blank 15 is placed in the apparatus with the body of the blank resting upon the support 12 and with the flanges 7a and 7b extending upwardly. The ram 22 is then lowered to bring the mandrel 27 between the flanges and 20 into engagement with the body of the blank to hold the same against the member 12. Upon further downward movement of the ram 22, the bearing plates 33 engage the top surface of the dies 35 to move the same downwardly together with the plate 15. In the course of the downward movement of the dies, the blocks 40 are brought into engagement with the cams 42 whereby the dies are moved inwardly in a direction perpendicular 30 to the direction in which they are moved solely by the ram, thereby imparting a resultant movement to the dies inclined to the member 12 and mandrel 27 to cause the blocks 36 to engage the flanges to fold them along 35 the lines of previous bend. In this manner the portions 7c and 7d of flanges 7b and 7a respectively are brought against the mandrel 27 and the portions 7e and 7f of the flanges 7b and 7a respectively against the 40 body of the blank upon the member 12.

When the blank has been shaped in this manner, the ram 22 is raised to remove the mandrel 27 from the blank and the plates 33 from the dies 35. At the same time the 45 springs 20 raise the plate 15 together with the dies 35, and the springs 49 act upon the dies to move them outwardly along the cams 42. During this operation each flange on one side of the body 7 of the blank is offset while 50 only the central flange upon the other side of the body is offset.

We claim:

1. In an apparatus for shaping sheet metal previously bent with a flange, the combination of a member for supporting the body of said bent metal, a mandrel movable towards said member against the body of the metal, a die movable in a path inclined to said member, means for movably supporting said die, 55 and means for urging said die simultaneously in perpendicular directions thereby imparting a resultant movement thereto in a direction inclined to said member to move said flange against said mandrel and the body of 60 the metal on said member.

2. In an apparatus for shaping sheet metal previously bent with a flange, the combination of a member for supporting the body of said bent metal, a mandrel movable towards 70 said member against the body of the metal, a support yieldingly mounted near said member, a die movable with and relative to said support, means for moving said die and support, and means for moving said die relative to said support.

3. In an apparatus for shaping sheet metal previously bent with a flange, the combination of a member for supporting the body of the metal, a ram movable towards and from 75 said member, a mandrel yieldingly mounted on said ram and adapted to engage the body of said metal, a support yieldingly mounted near said member, a die movable with and relative to said support, means for moving said die and support, and means for moving 80 said die relative to said support.

In testimony whereof we affix our signatures.

OTTO J. GROEHN.

LAWRENCE S. LAMB.
